UNITED STATES PATENT OFFICE.

WALTER KENNISON, OF ALAMEDA, CALIFORNIA.

FIRE DOOR, SCREEN, AND THE LIKE FOR BUILDINGS.

Application filed April 19, 1924. Serial No. 707,682.

To all whom it may concern:

Be it known that I, WALTER KENNISON, a citizen of the United States, residing at Alameda, in the county of Alameda and State of California, have invented a new and useful Improvement in Fire Doors, Screens, and the like for Buildings, of which the following is a specification.

My invention relates in general to fire doors, screens and the like for buildings and has reference more particularly to an improved rolling fire door of the type that is automatically released to a closing position relative to a door way or the like when a fire occurs in the vicinity of the same.

The primary object of my invention is to improve the construction, operation, and effectiveness of this class of apparatus and the preferred embodiment of the structure is illustrated in the accompanying drawings. In said drawings, Fig. 1 is a view in front elevation of the door illustrating its application to an opening to be protected; Fig. 2 is a vertical section through the door on the line 2—2, Fig. 1; Fig. 3 is a detail view in side elevation of the dogging device that cooperates with the fusible restraining structure of the assembly; Fig. 4 is a detail view in section of the dogging device taken on the line 4—4, Fig. 3. Fig. 5 is a horizontal sectional view of the door winding barrel, taken on the line 5—5, Fig. 1; Fig. 6 is an enlarged cross section of the door winding barrel and its associated parts; and Fig. 7 is a vertical section of the door per se showing its sectional assembly.

Referring now to the drawings in detail, 1 represents a doorway or other like communication, and 2 represents the door per se which, according to the illustration, should be of the rolling type, and for this reason it is made in hingedly connected sections. The door, 2, is suspended in front of the doorway, 1, and maintained in an inactive position, rolled upon the winding barrel, 3. In operation a fusible restraining device (to be hereinafter described) is associated with the winding barrel, 3, so that ordinarily the door will be wound up out of the way and thus leaving the doorway unobstructed. Should a fire occur in the vicinity of the assembly the fusible restraining device will automatically function to release the door and the same will move to an active position, closing off the doorway.

The upper edge of the door is fixed to the

barrel by the screws, 4, or by any other means suitable for the purpose.

The barrel, 3, is mounted with freedom of rotation within a suitable housing, 5, which in turn is mounted above the doorway, 1, and the housing is made with supporting bearings, 6, at its respective ends to accommodate the ends, 7, of a pair of shafts, 8, and 9, with which the barrel is equipped. These shafts are indirectly connected to the barrel by a pair of oppositely acting coil springs, 10 and 11. The protruding end of the shaft, 9, is provided with a ring, 12, which is fixed to the shaft by a pin, 13, and the ring is adapted to be held against rotation by means that locks it to the housing, 5.

The opposite end of the shaft, 9, terminates in a sleeve, 14, and the sleeve is fixed to the barrel by a set screw or the like, 15. The sleeve is made with a reduced extension, 16, to receive and anchor the spring end. The opposite end of the spring is anchored to a sleeve, 17, which is loose on the shaft, 8, and a collar, 18, behind the sleeve, 17, is fixed to the barrel by a set screw, 19, but the collar is not fixed to the shaft.

The assembly for the shaft, 8, is substantially the same as for the shaft, 9; that is, a collar, 20, on the shaft is fixed to the barrel with the reduced extension 21 thereof made to receive and anchor the spring, 10, and the opposite end of the spring is anchored to the reduced extension 22 of the sleeve, 23, which in turn is loose on the shaft.

Each end of the barrel is provided with a guide flange, 24, which may be made as a part of the collars, 18 and 25.

Mounted upon and fixed to the shaft, 8, on the outside of the guide, 24, is a notched wheel, 26, which forms a part of the fusible restraining device. This wheel, 26, cooperates with a dog, 27, on the rod, 28. This rod extends into the housing and terminates in a bearing, 29. A spring, 30, coiled on the rod, 28, is fixed to rotate the rod so as to move the dog, 27, out of the notch in the wheel. A support, 31, is provided for holding the rod.

Carried on the end of the rod, 28, is an arm, 32, which extends along the front of the housing with an eye, 33, on its end. This eye is adapted to be hooked or otherwise fastened to a chain or the like, 34, which embodies in its construction a fusible ele-

ment, 35. The end of the chain is anchored as at 36, to a shield, 38, after it passes through an opening in the housing as at 39. The shield, 38, is hinged in the housing and 5 when the fusible device is connected to the arm, 32, the shield is pulled toward the curved wall of the housing, but the weight of the same automatically moves it to a position, as best shown in Fig. 6 when the 10 fusible element is fused, so that it bears against the door guide, 40, to seal the bottom of the housing against flames.

Operation.

15 The springs, 10 and 11, are coiled in opposite directions and they have a counterbalancing effect on the barrel and the door wound thereon. The spring, 11, is longer and thus stronger than the spring, 10. The 20 latter unwinds the barrel when urged by the weight of the door, and the spring, 11, is wound up when the door goes down. The tension thus placed on the spring, 11, can be utilized to advantage when the door is 25 raised; in other words, it will help relieve the weight of the door when it is raised and also wind it upon the barrel.

To set the door, it is, of course, first raised and wound upon the barrel. When it has 30 reached the termination of its upward movement the outrigger flanges, 41, meet the edge of the opening, in the bottom of the housing. The arm, 32, is then raised by the operator and fastened to the chain, 34. The movement of the arm to this position rotates the 35 rod, 28, which in turn seats the dog, 27, in one of the notches in the wheel, 26. When so engaged the wheel will be arrested, which in turn will arrest the spring, 10, and 40 through it the barrel. The door will thus be maintained in a raised inactive position.

When the heat melts the fusible element, 35, and releases the arm, 32, the spring, 30, on the rod, 28, rotates the rod and disengages 45 the dog, 27, so that the wheel, 26, is free to rotate and the spring 10 drops the door. The shield, 38, is also released by this action,

and the same moves into position as shown in Fig. 6. When the door is to be raised, the operator simply lifts the same, and with the 50 help of spring, 11, no unusual effort is required. After being raised a new fusible element may replace the one destroyed, and the arm, 32, fastened into position.

I claim:

1. In a rolling door of the class described, a barrel to which the door is fastened and upon which it is adapted to wind and unwind, a housing for said barrel, an opening in the bottom of said housing, a door guide projecting into said opening, a shield hingedly connected in said housing, a thermo-control for holding the door wound upon the barrel, said thermo control embodying in its construction a fusible element, a connection between said fusible element and said shield adapted to hold the shield away from the barrel when the door is wound upon the barrel but releasing the shield when the thermo-control releases the door, said shield 70 when released adapted to rest against the door guide to close the opening in the bottom of the housing.

2. In a rolling door of the class described, a barrel to which the door is fastened and 75 upon which it is adapted to wind, and unwind, a housing for the barrel having an opening in the bottom thereof through which the door passes, a shield in said housing for closing the opening in the bottom thereof 80 when the door is unwound from the barrel, means for holding the door wound upon the barrel, a chain having a fusible element embodied in the construction thereof connected at one end to the door holding means and 85 with its opposite end connected to said shield, said connection between the chain and shield adapted to hold the shield away from the opening in the bottom of the housing, and the fusing of the fusible element 90 adapted to release the shield and likewise the door holding means.

WALTER KENNERTON.
